DISPLAY CASE FOR FOUNTAIN PENS
OR THE LIKE

Virgil S. Simon, Glenview, Ill.

Application May 2, 1958, Serial No. 50,735

Term of patent 14 years

(Cl. D80—11)

Figure 1 is a perspective view of a display case for fountain pens or the like, embodying my new design;

I claim:

The ornamental design for a display case for fountain pens or the like, substantially as shown.
